UNITED STATES PATENT OFFICE

JOHN T. MCCROSSON, OF PORT AU PRINCE, HAITI, ASSIGNOR TO FRESH-KEEPING
PACKAGE CORPORATION, A CORPORATION OF DELAWARE

PACKAGE FOR CIGARS, CIGARETTES, AND SMOKING TOBACCO

Application filed April 3, 1928. Serial No. 267,024.

The invention relates to packages for tobacco and the like and method of making the same, being primarily intended for packages of pocket size, or other convenient sizes, of 5 cigars, cigarettes and smoking tobacco.

Important objects of my invention are to produce packages of substantially hermetic character which will preserve the tobacco fresh and in good natural smoking condition 10 for a reasonable length of time, and kill insects and prevent the development of their eggs; also to provide such packages constructed to display the goods attractively; also to provide such packages as are adapted 15 to be constructed, filled and sealed by machinery so as to reduce the expense of these operations and of the marketing of the goods in well preserved and attractive form.

My present improvements are designed to 20 efficiently carry into use the process which is the subject of my Patent No. 1,458,586, granted June 12, 1923, for a method or process of packing and preserving cigars, cigarettes and smoking tobacco by the substitution of 25 an inert gas in place of air within the package so as to penetrate, surround and preserve the goods, with the benefits set forth in my said patent.

The improvement in the manufacture of 30 cellophane, which is transparent and is now made both air and moistureproof, makes it most desirable as a covering for my package in carrying out the process of my said patent, and my present invention comprises a 35 new manner, suitable for the operations of packing machines, of applying, combining and utilizing the cellophane in my improved package for sealing the same and displaying the goods.

40 The modern packing machine will wrap and seal sixty to seventy packages of cigars or cigarettes per minute when the article operated upon is fed to the machine in suitable form to be wrapped and sealed.

45 To facilitate the work of the machines and enable them to work up to their full capacity, I have found it desirable to provide a cardboard skeleton frame which has been treated with cellophane glue or other airtight solution. These skeleton frames, filled with the

article to be treated, are fed to the machines and wrapped with the cellophane covering which in the same operation is glued to said skeleton frame. The packages are then vacuumized and filled with inert gas, as described in my Patent 1,458,586. The articles enclosed and preserved in this package are plainly visible through the cellophane on the top or bottom of said package, or on both, while the skeleton frame maintains the package in shape for wrapping, handling and storage.

In the case of small or larger packages the skeleton frame may be provided with an outer cardboard covering into which it is slid for 55 protection in shipping and handling. A portion of the top side of this protective covering may be and is preferably cut away to provide a view of the contents of the vacuumized and gas-filled package within.

In order to make the invention more readily understood, I have shown in the accompanying drawings means for carrying the same into effect, and for explaining the steps of the method, but the invention is not confined, in its useful applications, to the details herein set forth for the purpose of explanation.

In said drawings—
Fig. 1 is a plan view of a blank of cardboard or stiff paper, which is to be formed into an end section for the package.

Fig. 2 is a perspective view of the same formed into such a section.

Fig. 3 is a perspective view of two end sections, which are preferably counterparts of each other, filled with cigars and put together and ready for the application of the cellophane wrapper, said view showing also 85 said wrapper partly applied.

Fig. 4 is a perspective view of the package sealed and completed, showing also the outer protecting frame into which the package may slide.

Fig. 5 is a perspective view of another form of the inner part or frame of the package, comprising two separate end sections which are not counterparts but are of different forms.

Fig. 6 shows the same constructed so as to be formed of three pieces.

Referring to the drawings,

1 indicates a blank suitable to form an end section 2 of the package. This blank is of card board or sufficiently thick and stiff paper to maintain the form of the section, and is moulded or drawn by pressure with the aid of moisture and heat into the form shown in Fig. 2 so as to have an end panel 3, a bottom part 4, sides 5 and top flanges 6, 7 and 8. All these parts of the section are preferably integral and continuous with each other, so that each end section is without cracks and 15 gas-tight at its angles; but a hole 11 for the exit of air and entrance of gas is provided at a convenient point.

As illustrated the bottom parts 4 of the sections form one half of the bottom panel 20 of the package but can be in the form of flanges like the flanges 6, 7 and 8 to display the goods at the bottom as well as at the top of the package.

The sections may be shaped so as to fit 25 each other end to end and also have sufficient edgewise engagement with each other where they fit together to keep one another in line during the wrapping operation. The sections may be shaped so as to be counterparts 30 of each other.

In making the package two of the sections are brought together end to end at the same time enclosing the goods to be packed, cigars 35 for example, and are conveyed to the wrapping station of the machine. Here they will arrive on the wrapper 9, preferably of cellophane, and the latter will be wrapped to enclose the top, bottom and sides of the sections 2. The wrapper 9 is of substantially 40 a width equal to the length of the two sections, and need not extend so as to require to be folded over the ends 3, and mechanism for such folding may be dispensed with. In this wrapping operation the wrapper is 45 caused to adhere in a gas-tight manner to the two sections 2 on lines surrounding the tops, bottoms and sides of the sections. This is effected by applying cellophane glue along 50 the end edges 10 of the wrapper, or correspondingly around the sections, before or during the wrapping operation. The end sections are preferably dipped in cellophane 55 solution or glue for a short distance from their ends to prevent diffusion of the gas through the card board or paper of which the sections are composed, and to promote complete and gas-tight adhesion of the cellophane wrapper to the sections.

60 The end sections may be formed of slightly different cross-dimensions and the open end of one section slid a little way into the open end of the other section as the cigars are being enclosed in the package, after which 65 the filled sections are wrapped as above de-

scribed, such a construction being shown in Fig. 5.

After the package is wrapped and sealed as above described it (or a number of such packages) is placed in a chamber and air exhausted from the chamber, which will withdraw substantially all air out of the package or packages through the hole 11. Then an inert gas, preferably nitrogen gas, is admitted to the chamber at atmospheric pressure and 70 will enter the hole 11 and fill all unoccupied spaces within the vacuumized package. Then the gas-treated package (or packages) is removed from the chamber and an adhesive piece 12 of cellophane is pressed on the package 75 to adhere to the same and seal the hole 11. 80

In Fig. 5 I have illustrated a construction of the inner part or frame of the package of which the wrapper 9 is not yet applied, especially adapted for smoking tobacco or snuff. 85 In this construction the bottom, sides and top flanges are on one end section only, and the other end section has an end panel with short top, bottom and side flanges, and the bottom, sides and top flanges of the first mentioned 90 section are entered within the second short section at the filling operation, after which the wrapper is applied and the package gasified as already described.

It will be understood that the package may 95 be used to contain any goods, besides tobacco, for which it is adapted.

The herein described package, after it is completed, ready for sale, is usually inserted by slipping into an exterior protecting frame 100 shown at 13 in Fig. 4, having an opening on its top corresponding with the transparent top of the package.

As shown in Fig. 6 the bottom, sides and longitudinal flanges of the middle part of the package are not formed with either of the end sections, but said end sections engage outside of these intermediate parts as the filling of the package and the end sections are brought together prior to the wrapping. 105

These end sections 2 are or may be formed in the manner described for the end section shown in Fig. 2 but the blank will be smaller and of different shape, as will be readily understood. 110

I claim:

1. A package having in combination separate end sections each formed with top flanges and bottom portions and molded at their angles to retain gas and adapted to be brought together longitudinally to enclose cigars and the like and display the same and having longitudinal shoulders engaging each other edgewise to aid in maintaining said sections in line with each other, and a transparent wrapper surrounding the top, bottom and sides of the end sections and having its edges glued to the same on lines surrounding the end sections, to seal the joint line between said end sections and form a gas-tight display pack- 115 120 125 130

age, said package being charged with inert gas.

2. A package having in combination separate end sections each formed with top flanges and bottom portions and molded at their angles to retain gas and adapted to be brought together longitudinally to enclose cigars and the like and display the same and having longitudinal shoulders engaging each other 10 edgewise to aid in maintaining said sections in line with each other, and a transparent wrapper surrounding the top, bottom and sides of the end sections and having its end edges glued to the same on lines surrounding 15 the end sections, to seal the joint line between said end sections and form a gas-tight display package, said package being charged with inert gas, and an aperture formed in one of said end sections to permit air to be exhausted 20 from an assembled filled package, said aperture being adapted to be hermetically sealed after an inert gas has been substituted for the exhausted air.

In testimony whereof I affix my signature.
JOHN T. McCROSSON.
